(57) CLAIM

The ornamental design for a shoe, as shown and described.

DESCRIPTION

FIG. 1 is a front, right-side perspective view of a shoe in accordance with my new design;

FIG. 2 is a front, left-side perspective view of the shoe shown in FIG. 1;

FIG. 3 is a front view of the shoe shown in FIG. 1;

FIG. 4 is a rear view of the shoe shown in FIG. 1;

FIG. 5 is a left-side view of the shoe shown in FIG. 1;

FIG. 6 is a right-side view of the shoe shown in FIG. 1;

FIG. 7 is a top view of the shoe shown in FIG. 1; and,

FIG. 8 is a bottom view of the shoe shown in FIG. 1.

The broken lines surrounding the unshaded areas on the shoe upper represent the bounds of the claimed design. The broken lines illustrating unclaimed laces and all other broken lines are directed to environment and are for illustrative purposes only; the broken lines form no part of the claimed design. The stippling represents a contrast in texture, relative to the non-stippled areas of the shoe.
